EX

OR D 21,082

UNITED STATES PATENT OFFICE.

JULIUS PEGEL, OF PHILADELPHIA, PENNSYLVANIA, ASSIGNOR TO JOHN BROMLEY & SONS.

DESIGN FOR A TABLE-COVER, &c.

UNITED STATES PATENT OFFICE.

EDWARD POOLE, OF PHILADELPHIA, PENNSYLVANIA, ASSIGNOR TO JOHN BROMLEY & SONS.

DESIGN FOR A TABLE-COVER.

SPECIFICATION forming part of Design No. 21,082, dated September 29, 1891.

Application filed August 31, 1891. Serial No. 404,349. Term of patent 3½ years.

To all whom it may concern:

Be it known that I, EDWARD POOLE, a subject of the Queen of Great Britain, residing at Philadelphia, Pennsylvania, have invented or 5 produced a certain new and original Design for a Table-Cover, of which the following is a full, clear, and exact description, reference being had to the accompanying drawing, forming a part of this specification.

10 My invention relates to the surface ornamentation of a table-cover; and it consists of the design therefor shown in the accompanying photographic illustration.

I claim as my invention—

The design for a table-cover, substantially 15 as shown and set forth.

In testimony whereof I have hereunto affixed my signature this 13th day of July, A. D. 1891.

EDWARD POOLE.

Witnesses:

WM. L. TURNER,
EDWARD BROMLEY.
